tion of Delaware

Application December 20, 1940, Serial No. 370,959

21 Claims. (Cl. 123—169)

This invention relates to an improvement in spark plugs for internal combustion engines, and it is applicable to either the so-called two-piece gland nut type of construction or the one-piece crimped shell type of construction.

An object of the present invention is to so constitute spark plugs of this character that they will have an extremely high and effective resistance to electrical "flash-over" or discharge from the high tension terminal at the outer end of the center electrode to the metal shell or gland nut, and to accomplish this in a simple and comparatively inexpensive and practical manner while preserving all of the advantages of the standard or conventional spark plug.

Other objects and advantages reside in certain novel features of the construction, arrangement, and combination of parts, which will be hereinafter more fully described and particularly pointed out in the appended claims, reference being had to the accompanying drawing forming a part of this specification, and in which:

Figure 1 is a view partly in vertical diametrical cross section and partly in side elevation showing a spark plug of the gland nut type embodying one form of the present invention;

Figure 2 is a view similar to Figure 1 and showing the same form of the invention incorporated in a spark plug of the so-called one-piece crimped shell type;

Figure 3 is a view similar to Figures 1 and 2 but showing another form of the present invention embodied in a spark plug of the gland nut type;

Figure 4 is a view similar to Figures 1 to 3 but showing the form of the invention illustrated in Figure 3 incorporated in a spark plug of the so-called one-piece crimped shell type; and

Figure 5 is a fragmentary view similar to Figure 4 but showing a structural variant of the form of the invention illustrated in Figure 4.

Referring to the drawing, it will be seen that in all embodiments of the present invention a spark plug is provided which comprises a bushing or metallic shell-like body 10 which has its lower end reduced and externally threaded, as at 11, to adapt it to be screwed into an internally threaded opening of a cylinder head of an internal combustion engine. The outer end of the metallic shell 10 is provided with a hexagon formation 12 to adapt it to coact with a wrench or suitable tool to facilitate the installation and removal of the plug. An insulator 13, usually of porcelain or ceramic material, is associated with the metallic shell 10. An inner gasket 14 is inter-

posed between the insulator 13 and the metallic shell 10 in the usual way. An outer gasket 15 is also provided.

In the construction shown in Figures 1 and 3 a packing gland nut 16 is threaded into the upper end of the metallic shell 10 and engages the gasket 15, thereby hermetically sealing the packing nut 16 to the insulator 13 of the plug and also compressing the gasket 14 to effect a hermetic seal between the insulator 13 and the shell 10.

In lieu of utilizing a packing or gland nut, such as nut 16, for compressing the inner and outer gaskets 14 and 15, and thereby setting up the desired seal between the insulator 13 and the shell 10, this may be accomplished by spinning, crimping, or forming over the upper portion 10' of the metallic shell in the manner illustrated in Figures 2, 4, and 5.

20 A center electrode 17 is combined with the insulator 13 in the usual way. The inner end of the center electrode is cooperatively related to one or more side electrodes 18. The outer end or high tension terminal of the center electrode is equipped with the usual terminal nut 19.

25 In the form of the invention shown in Figure 1, a cap of electrical insulating material, designated generally at 20, is applied over the portion of the insulator which is adjacent the gland nut 16. The cap 20 has a thick body portion 21 provided with a central opening 22 through which a portion of the insulator 13 extends. The flange 23 of the cap projects down over the outside of the gland nut 16 and bears against the top of the metallic shell 10. The cap is molded or otherwise formed of insulating material, such as rubber, synthetic rubber, synthetic elastic insulating material, elastic insulating material, or the like. Preferably the internal diameter of the opening 22 in the body 21 thereof is slightly less than the external diameter of the portion of the insulator 13 which it engages so that the body 21 of the cap must be stretched to assemble it with the insulator 13, and when assembled is still slightly stretched so as to insure a tight surface-to-surface contact or fit between the inner wall of the opening 22 and the portion of the outer periphery of the insulator 13 with which the inner wall of the opening 22 engages. This desired contact 30 and tight fit may further be enhanced by cementing the inner wall of the opening 22 to the portion of the insulator 13 which it engages.

35 In some instances, also, it may be desirable to further insure the maintenance of the assembly of the insulating cap 20 with the insulator

13, and this may be accomplished by forming an integral annular rib or bead 24 on the insulator 13 in such position that it engages the top surface of the cap 28 to positively retain it in place.

When assembled in the manner described, the protective or shielding cap provides a high and effective resistance to electrical "flash-over" or discharge from the high tension terminal 19 at the outer end of the center electrode to the packing or gland nut 18 and to the metallic shell 10.

In the form of the invention shown in Figure 2, a similar protective cap or shield, designated generally at 25, is provided, and in fact in all essential respects is the same as the protective or shielding cap 28 except that its dimensions are varied to adapt it to contact with the so-called one-piece crimped shell type of spark plug. In this instance a shoulder 26 may be formed on the insulator 13 to engage the top of the cap 25 for positively holding or retaining it in position. The under side of the body of the cap 25, as well as its flange 28, are preferably in close and tight engagement with the crimped-over end 18' of the shell 10, due to the fact that the cap is stretched when fitted over these parts. However, when the insulating caps 26 and 25 are cemented to their respective insulators 13 it is not necessary to provide the rib 24 in the one instance, nor the shoulder 26 in the other.

In the form of the invention shown in Figure 3, in lieu of a molded or preformed cap of electric insulating elastic material of the relatively substantial dimensions shown and described, the cap may be in the form of a coating or layer of electrical insulating material, designated generally at 30, applied around the top and over the outside of the gland nut and across the top of the metallic shell 10 in the manner illustrated in the drawing. This cap 30 of electrical insulating material may be painted, sprayed, molded, pressed, fused, or cemented to the surfaces to which it is applied. Any suitable plastic material, which is electrically insulating, has the requisite bonding properties, is capable of withstanding the temperature to which it is subjected, and chemically inert in its environment, may be used, or any liquid electrical insulating material, which is settable after application, and which has the properties mentioned, may be employed. A cement which has synthetic rubber as its base, has been successfully used. Insulating coatings of ceramic or porcelain insulating cement or enamel, or high dielectric insulating enamel, paint, or plastic, will serve effectively.

In the form of the invention shown in Figure 4, a cap of electrical insulating material, designated at 31, but similar to cap 30, is applied over the crimped portion of the metallic shell 10, and over the upper portion of the metallic shell proper, in the manner illustrated in the drawing. This cap 31 is similar in its composition to the cap 30, the only difference between the construction shown in Figures 3 and 4 being that Figure 4 illustrates how a coating or cap of electrical insulating material may be applied to the one-piece crimped shell type of spark plug. If desired, the cap or coating of insulating material applied to the one-piece crimped type of spark plug, instead of terminating at the top of the hexagon of the metallic shell, may be extended down to cover the outer surface of the hexagon, as indicated at 32 in Figure 5. Ordinarily, and preferably, however, the external dimensions of the caps 20, 25, 30 and 31 are such as to lie within the confines of the external dimensions of the hexagon 75

formation 12 at the upper end of the metallic shell 10 of each plug, as it is desirable to leave the peripheral surface of the hexagon formation 12 uncovered so that its adaptability for coaction with a wrench or other suitable tool is not impaired.

In all forms of the invention there is presented a high and effective resistance to electrical flash-over or discharge from the high tension terminal at the outer end of the center electrode to the metallic shell or gland nut of the spark plug, and this is accomplished without increasing the overall dimensions of the plug, or otherwise impairing its advantages and usefulness or the facility with which it may be installed or removed. In fact, the plug presents a standard or normal appearance and may be manufactured with economy and by means of facilities and from materials ordinarily available.

While I have shown and described several constructions in which the invention may be advantageously embodied, it is to be understood that the constructions shown have been selected merely for the purpose of illustration or example, and that various changes in the size, shape, and arrangement of the parts may be made without departing from the spirit of the invention or the scope of the subjoined claims.

I claim:

1. A spark plug comprising a metallic shell, an insulator having an inner portion disposed in the shell, and an outer portion projecting outwardly therefrom, cooperating structure on the shell and on the portion of the insulator disposed therein and including metallic means at the outer end of the shell for securing and hermetically sealing the insulator to the shell, a high tension terminal projecting beyond the outer end of the insulator, and a cap of electrical insulating material covering and conforming to the contour of said metallic means and in tight surface-to-surface engagement with the part of the peripheral surface of the outer projecting portion of the insulator adjacent said means, the outer portion of the insulator projecting beyond said cap, the cap coacting with the portion of the insulator extending between the cap and the high tension terminal to provide a high and effective resistance to electrical flash-over or discharge from the high tension terminal to said means and said shell.

2. A spark plug comprising a metallic shell, an insulator having an inner portion disposed in the shell, and an outer portion projecting outwardly therefrom, co-operating structure on the shell and on the portion of the insulator disposed therein and including metallic means at the outer end of the shell for securing and hermetically sealing the insulator to the shell, a high tension terminal projecting beyond the outer end of the insulator, and a cap of elastic electrical insulating material surrounding and in stretched engagement with the outer portion of the insulator immediately above said metallic means and conforming to the contour of and covering said metallic means and overlying the outer end of said shell, the outer portion of the insulator projecting beyond said cap, the cap coacting with the portion of the insulator extending between the cap and the high tension terminal to provide a high and effective resistance to electrical flash-over or discharge from the high tension terminal to said metallic means and said shell.

3. A spark plug comprising a metallic shell, an insulator having an inner portion disposed in the

shell, and an outer portion projecting outwardly therefrom, co-operating structure on the shell and on the portion of the insulator disposed therein and including metallic means at the outer end of the shell for securing and hermetically sealing the insulator to the shell, a high tension terminal projecting beyond the outer end of the insulator, and a cap of elastic electrical insulating material surrounding and in stretched engagement with and cemented to the outer portion of the insulator immediately above said metallic means and conforming to the contour of and covering said metallic means and overlying the outer end of said shell, the outer portion of the insulator projecting beyond said cap, the cap coacting with the portion of the insulator extending between the cap and the high tension terminal and providing a high and effective resistance to electrical flash-over or discharge from the high tension terminal to said metallic means and said shell.

4. A spark plug comprising a metallic shell, an insulator having an inner portion disposed in the shell, and an outer portion projecting outwardly therefrom, co-operating structure on the shell and on the portion of the insulator disposed therein and including metallic means at the outer end of the shell for securing and hermetically sealing the insulator to the shell, a high tension terminal projecting beyond the outer end of the insulator, and a cap of elastic electrical insulating material surrounding and in stretched engagement with the outer portion of the insulator immediately above said metallic means and conforming to the contour of and covering said metallic means and overlying the outer end of said shell, the outer portion of the insulator projecting beyond said cap, the cap coacting with the portion of the insulator extending between the cap and the high tension terminal and providing a high and effective resistance to electrical flash-over or discharge from the high tension terminal to said metallic means and said shell, the outer portion of the insulator having a downwardly facing shoulder engageable with the top of the insulating cap to positively retain it in position.

5. A spark plug comprising a metallic shell, an insulator having an inner portion disposed in the shell and an outer portion projecting outwardly therefrom, means including a gland nut threadedly connected with the outer end of the shell for securing and hermetically sealing the insulator to the shell, a high tension terminal projecting beyond the outer end of the insulator, and a cap of electrical insulating material covering and conforming to the contour of said gland nut and in tight surface-to-surface engagement with the part of the peripheral surface of the outer projecting portion of the insulator adjacent said gland nut, the outer portion of the insulator projecting beyond said cap and coacting therewith to provide a high and effective resistance to electrical flash-over or discharge from the high tension terminal at the outer end of the insulator to said gland nut and said shell.

6. A spark plug comprising a metallic shell, an insulator having an inner portion disposed in the shell and an outer portion projecting outwardly therefrom, means including a gland nut threadedly connected with the outer end of the shell for securing and hermetically sealing the insulator to the shell, a high tension terminal projecting beyond the outer end of the insulator, and a cap of elastic electrical insulating material sur-

rounding and in stretched engagement with the outer portion of the insulator immediately above said gland nut and conforming to the contour of and fitted over and covering said gland nut and overlying the outer end of said shell, the outer portion of the insulator projecting beyond said cap and coacting therewith to provide a high and effective resistance to electrical flash-over or discharge from the high tension terminal at the outer end of the insulator to said gland nut and said shell.

7. A spark plug comprising a metallic shell, an insulator having an inner portion disposed in the shell and an outer portion projecting outwardly therefrom, means including a gland nut threadedly connected with the outer end of the shell for securing and hermetically sealing the insulator to the shell, a high tension terminal projecting beyond the outer end of the insulator, and a cap of elastic electrical insulating material surrounding and in stretched engagement with and cemented to the outer portion of the insulator immediately above said gland nut and conforming to the contour of and fitted over and covering said gland nut and overlying the outer end of said shell, the outer portion of the insulator projecting beyond said cap and coacting therewith to provide a high and effective resistance to electrical flash-over or discharge from the high tension terminal at the outer end of the insulator to said gland nut and said shell.

8. A spark plug comprising a metallic shell, an insulator having an inner portion disposed in the shell and an outer portion projecting outwardly therefrom, means including a gland nut threadedly connected with the outer end of the shell for securing and hermetically sealing the insulator to the shell, a high tension terminal projecting beyond the outer end of the insulator, and a cap of elastic electrical insulating material surrounding and in stretched engagement with the outer portion of the insulator immediately above said gland nut and conforming to the contour of and fitted over and covering said gland nut and overlying the outer end of said shell, the outer portion of the insulator projecting beyond said cap and coacting therewith to provide a high and effective resistance to electrical flash-over or discharge from the high tension terminal at the outer end of the insulator to said gland nut and said shell, the outer portion of the insulator having a downwardly facing shoulder immediately above and in engagement with the top of the insulating cap to positively retain it in position.

9. A spark plug comprising a metallic shell, an insulator having an inner portion disposed in the shell and an outer portion projecting outwardly therefrom, means including an inward crimp on the outer end of the shell for securing and hermetically sealing the insulator to the shell, a high tension terminal projecting beyond the outer end of the insulator, and a cap of electrical insulating material covering and conforming to the contour of said inward crimp and in tight surface-to-surface engagement with the part of the peripheral surface of the outer projecting portion of the insulator adjacent said inward crimp, the outer portion of the insulator projecting beyond the cap and coacting therewith to provide a high and effective resistance to electrical flash-over or discharge from the high tension terminal at the outer end of the insulator to said inward crimp and said shell.

10. A spark plug comprising a metallic shell,

an insulator having an inner portion disposed in the shell and an outer portion projecting outwardly therefrom, means including an inward crimp on the outer end of the shell for securing and hermetically sealing the insulator to the shell, a high tension terminal projecting beyond the outer end of the insulator, and a cap of elastic electrical insulating material surrounding and in stretched engagement with the outer portion of the insulator immediately above said inward crimp and conforming to the contour of and covering said crimp and overlying the outer end of said shell, the outer portion of the insulator projecting beyond said cap and coacting therewith to provide a high and effective resistance to electrical flash-over or discharge from the high tension terminal at the outer end of the insulator to said metallic means and said shell.

11. A spark plug comprising a metallic shell, an insulator having an inner portion disposed in the shell and an outer portion projecting outwardly therefrom, means including an inward crimp on the outer end of the shell for securing and hermetically sealing the insulator to the shell, a high tension terminal projecting beyond the outer end of the insulator, and a cap of elastic electrical insulating material surrounding and in stretched engagement with and cemented to the outer portion of the insulator immediately above said inward crimp and conforming to the contour of and covering said crimp and overlying the outer end of said shell, the outer portion of the insulator projecting beyond said cap and coacting therewith to provide a high and effective resistance to electrical flash-over or discharge from the high tension terminal at the outer end of the insulator to said metallic means and said shell.

12. A spark plug comprising a metallic shell, an insulator having an inner portion disposed in the shell and an outer portion projecting outwardly therefrom, means including an inward crimp on the outer end of the shell for securing and hermetically sealing the insulator to the shell, a high tension terminal projecting beyond the outer end of the insulator, and a cap of elastic electrical insulating material surrounding and in stretched engagement with the outer portion of the insulator immediately above said inward crimp and conforming to the contour of and covering said crimp and overlying the outer end of said shell, the outer portion of the insulator projecting beyond said cap and coacting therewith to provide a high and effective resistance to electrical flash-over or discharge from the high tension terminal at the outer end of the insulator to said metallic means and said shell, the outer portion of the insulator having a downwardly facing shoulder immediately above and in engagement with the top of the insulating cap to positively retain it in position.

13. A spark plug comprising a metallic shell, an insulator having an inner portion disposed in the shell, and an outer portion projecting outwardly therefrom, cooperating structure on the shell and on the portion of the insulator disposed therein and including metallic means at the outer end of the shell for securing and hermetically sealing the insulator to the shell, a high tension terminal projecting beyond the outer end of the insulator, and a cap of electrical insulating material surrounding the part of the peripheral surface of the outer projecting portion of the insulator adjacent said means and covering said means and the outer end of the shell, said cap

comprising a layer of electrical insulating material bonded to said means and to the outer end of said shell and capable of withstanding high temperature and also being chemically inert in its environment.

14. A spark plug comprising a metallic shell, an insulator having an inner portion disposed in the shell, and an outer portion projecting outwardly therefrom, cooperating structure on the shell and on the portion of the insulator disposed therein and including metallic means at the outer end of the shell for securing and hermetically sealing the insulator to the shell, a high tension terminal projecting beyond the outer end of the insulator, and a cap of electrical insulating material surrounding the part of the peripheral surface of the outer projecting portion of the insulator adjacent said means and covering said means and the outer end of the shell, said cap comprising a coating of electrical insulating material.

15. A spark plug comprising a metallic shell, an insulator having an inner portion disposed in the shell, and an outer portion projecting outwardly therefrom, cooperating structure on the shell and on the portion of the insulator disposed therein and including metallic means at the outer end of the shell for securing and hermetically sealing the insulator to the shell, a high tension terminal projecting beyond the outer end of the insulator, and a cap of electrical insulating material surrounding the part of the peripheral surface of the outer projecting portion of the insulator adjacent said means and covering said means and the outer end of the shell, said cap comprising an insulating coating of synthetic rubber.

16. A spark plug comprising a metallic shell, an insulator having an inner portion disposed in the shell, and an outer portion projecting outwardly therefrom, cooperating structure on the shell and on the portion of the insulator disposed therein and including metallic means at the outer end of the shell for securing and hermetically sealing the insulator to the shell, a high tension terminal projecting beyond the outer end of the insulator, and a cap of electrical insulating material surrounding the part of the peripheral surface of the outer projecting portion of the insulator adjacent said means and covering said means and the outer end of the shell, said cap comprising a coating of insulating cement.

17. A spark plug comprising a metallic shell, an insulator having an inner portion disposed in the shell, and an outer portion projecting outwardly therefrom, cooperating structure on the shell and on the portion of the insulator disposed therein and including metallic means at the outer end of the shell for securing and hermetically sealing the insulator to the shell, a high tension terminal projecting beyond the outer end of the insulator, and a cap of electrical insulating material surrounding the part of the peripheral surface of the outer projecting portion of the insulator adjacent said means and covering said means and the outer end of the shell, said cap comprising a coating of insulating enamel of high dielectric constant.

18. A spark plug comprising a metallic shell, an insulator having an inner portion disposed in the shell, and an outer portion projecting outwardly therefrom, cooperating structure on the shell and on the portion of the insulator disposed therein and including metallic means at the outer end of the shell for securing and hermetically

sealing the insulator to the shell, a high tension terminal projecting beyond the outer end of the insulator, and a cap of electrical insulating material surrounding the part of the peripheral surface of the outer projecting portion of the insulator adjacent said means and covering said means and the outer end of the shell, said cap comprising an insulating coating of paint of high dielectric constant.

19. A spark plug comprising a metallic shell, an insulator having an inner portion disposed in the shell, and an outer portion projecting outwardly therefrom, cooperating structure on the shell and on the portion of the insulator disposed therein and including metallic means at the outer end of the shell for securing and hermetically sealing the insulator to the shell, a high tension terminal projecting beyond the outer end of the insulator, and a cap of electrical insulating material surrounding the part of the peripheral surface of the outer projecting portion of the insulator adjacent said means and covering said means and the outer end of the shell, said cap comprising a plastic insulating coating of high dielectric constant.

20. A spark plug comprising a metallic shell, an insulator having an inner portion disposed in the shell and an outer portion projecting outwardly therefrom, cooperating structure on the shell and on the portion of the insulator disposed therein and including metallic means at the outer end of the shell for securing and hermetically sealing the insulator to the shell, said shell having a hexagon formation at its outer end just inwardly of said metallic means, a high tension terminal projecting beyond the outer end of the insulator, and a cap of electrical insulating ma-

terial covering and conforming to the contour of said metallic means and in tight surface-to-surface engagement with the part of the peripheral surface of the outer projecting portion of the insulator adjacent said means, the cap lying entirely within the confines of said hexagon formation, the outer portion of the insulator projecting beyond the cap, the cap coacting with the portion of the insulator extending between the cap and the high tension terminal to provide a high and effective resistance to electrical flash-over or discharge from the high tension terminal to said means.

21. A spark plug comprising a metallic shell, an insulator having an inner portion disposed in the shell and an outer portion projecting outwardly therefrom, cooperating structure on the shell and on the portion of the insulator disposed therein for securing and hermetically sealing the insulator to the shell, a high tension terminal projecting beyond the outer end of the insulator, and a cap of electrical insulating material covering and conforming to the contour of the portion of said cooperating structure located at the outer end of the shell and in tight surface-to-surface engagement with the part of the peripheral surface of the outer projecting portion of the insulator adjacent said portion of said cooperating structure, the outer portion of the insulator projecting beyond said cap, the cap coacting with the portion of the insulator extending between the cap and the high tension terminal to provide a high and effective resistance to electrical flash-over or discharge from the high tension terminal to the outer end of the shell.

CHARLES R. BUENING.
